UNITED STATES PATENT OFFICE.

RALPH H. BROWN, OF WORCESTER, MASSACHUSETTS.

SOCKET-JOINT.

1,024,615.

Specification of Letters Patent.

Patented Apr. 30, 1912.

Application filed October 30, 1911. Serial No. 657,394.

To all whom it may concern:

Be it known that I, RALPH H. BROWN, a citizen of the United States, residing at Worcester, in the county of Worcester and 5 State of Massachusetts, have invented a new and useful Socket-Joint, of which the following is a specification.

This invention is particularly designed for use with cement filled columns, although 10 capable of use successfully with pipe, solid, or other columns.

The principal objects of the invention are to provide a construction for supporting the beams in such a way that the beams shall 15 apply a direct thrust to the socket joint itself instead of exerting a shearing strain upon the supporting platform, whereby the bending action on the platform is eliminated or decreased and the utility of the device is 20 greatly increased, and whereby for the same load a socket piece of much lighter construction can be employed; also to provide a construction for this purpose which shall be as near continuous as possible at the joint; 25 in which no holes for bolster screws will be required in the body of the column; and in which no screw threads have to be cut in the column as for a flange joint; to provide a construction in which the column suffers no 30 loss of transverse strength at the joint, and in which the joint can readily be inspected at the building and the size of all its parts measured before its erection.

Further objects and advantages of the invention will appear hereinafter.

Reference is to be had to the accompanying drawings in which—

Figure 1 is a plan of a socket joint and beam connection constructed in accordance 40 with this invention; and Fig. 2 is a central transverse sectional view thereof.

The invention is shown as applied to connect the lower column *a* and upper column *b* for the purpose of supporting horizontal 45 beams *c*. The socket joint is shown as comprising a cylindrical portion *D* having a diaphragm *d'* extending across the same, which may be perforated or not at *d*² as desired. This diaphragm is part-way between 50 the top and bottom and obviously the cylindrical body with the diaphragm affords two concentric sockets, one at the bottom for receiving the top of the lower column *a*, and the other at the top for receiving the 55 bottom of the upper column *b*. Integrally connected with the cylindrical shell is a

series of triangular supporting webs *d*³ having their apexes at the bottom and widened out at the top. These webs support the outer edges of a horizontal platform *d*⁴ which like the webs is integral with the socket and which extends outwardly from the top thereof and is flush with the top. This platform as will be seen, extends clear in to the surface of the upper column *b*. In 60 order to eliminate bending action on the platform or socket, in case the beam should be out of line, the platform may be curved downward at the outer edge as shown at *d*⁵. The beams may be bolted to the platform by 65 bolts *e* if desired. Where special rigidity is required as in a joint with an eccentric load, a cement grouting *f* can be introduced into the upper socket. From this construction it will be seen that the platform affords 70 a firm and rigid support for the beams, and that any desired number of beams can be supported upon it, either when it projects in only one or more directions from the center or when it is symmetrical around the 75 column.

The principal feature is that the beams project substantially into contact with the upper column, so that their ends rest directly over the vertical wall of the cylindrical joint. Consequently there is no shearing strain exerted by the beams on the platform itself. This is an advantage over such prior constructions as I am acquainted with 85 for the reason that they require a vertical 90 wall outside the upper column above the platform, and this wall prevents the beam being rested directly over the material of the cylindrical portion of the joint, and consequently necessitates the resting of the 95 end of the beam on the platform beyond the circumference of this cylindrical portion. This in the ordinary forms of beams exerts a shearing and bending strain on the platform which must be resisted by much more 100 metal than is the case with a direct thrust as is the case with my invention. It will be seen therefore that this result is secured by having the entire socket located below the platform and having it provided with a 105 socket for the upper column also located below the platform.

It will be seen that all the holes necessary for bolts or screws, are made in the platform and none need be made in the body of the 110 column. Thus a material source of weakness is completely avoided and another one

is avoided by reason of the fact that no screw threads are to be cut on the column for the flange joint. This socket is preferable to a connection made with flanges and pintles as the column suffers no loss of strength at the joint. Another advantage is that the joint can be inspected very readily at the building and the size of all its parts measured before it is erected, as no part of it is built into the column during construction. The end of the frame also can be brought up against the column.

Although I have illustrated and described a preferred form of the invention, I am aware that many modifications can be made in the same by any person skilled in the art without departing from the scope of the invention as expressed in the claim. Therefore I do not wish to be limited to the details of construction herein shown and described, but

What I do claim is:—

The combination with a lower column, of a socket piece having a cylindrical body 25 provided with a concentric downwardly opening socket fitting the top of said column, a diaphragm about midway between the top and bottom of the socket piece resting on the top of said column, and an up-

wardly opening cylindrical socket of substantially the same size as the lower socket, whereby it has cylindrical vertical walls bounding both sockets and integral with the diaphragm, said walls extending from the bottom of the socket piece materially above the diaphragm in the form of a uniform hollow cylinder, said socket piece being provided with a horizontal platform flush with its top and integral therewith, triangular webs extending from a point just below the diaphragm up to the platform and integral with both and having their widest dimension at the top, an upper column projecting about half way to the bottom of the socket piece and resting on said diaphragm, and beams resting on the top of said platform entirely above the socket piece and having their ends substantially in contact with the upper column and directly over the entire thickness of the vertical walls of the socket piece.

In testimony whereof I have hereunto set my hand, in the presence of two subscribing witnesses.

RALPH H. BROWN.
